TUBE BENDING MACHINE HAVING PRESSURE AND BACK UP RAMS

Walter P. Hill, Detroit, Mich., assignor to Aeroquip Corporation, Jackson, Mich., a corporation of Michigan

Application May 19, 1955, Serial No. 509,558

1 Claim. (Cl. 153—48)

This invention relates to a tube bending machine by which a straight tube section of bendable metal, such as aluminum, copper, or steel, is capable of being bent to have a smooth curved bend without collapse of the metal of the tube, or change in the wall thickness, whereby the initial interior and exterior tube diameters are closely maintained.

It is an object of the invention to provide a machine by which straight tube sections can be cold formed accurately into curved tube bends or elbows in an economical and efficient manner.

A further object of the invention is to provide a machine by which tube sections can be cold formed into accurate curved bends or elbows with the use of standard lubricants which can be readily removed and will not have any deleterious effect upon the tubes, such as occurs with the use of graphite in a known machine for forming tube bends with the use of a hot process.

The above, and further objects and advantages of the invention residing in the construction, operation and combination of parts will appear clear from consideration of the following description with reference to the drawings and from the appended claims.

In the drawings:

Fig. 1 is a plan view of a machine embodying the invention looking upon the bottom die structure, the upper die structure being broken away,

Fig. 2 is a side elevation of the machine, with the upper die in elevated position,

Fig. 3 is a vertically exploded elevation view of the upper and lower dies, on an enlarged scale compared with Figs. 1 and 2,

Fig. 4 is a perspective plan view of the lower die, with a filled tube in position for bending,

Fig. 5 is a detail view, showing a filled tube section in operative relation to the pressure plunger, and

Fig. 6 illustrates a completed tube bend, or elbow.

In the drawings, 10 indicates the base casing of the tube bending machine upon which casing there is mounted a bottom die pad 12 carrying a bottom die 14 having a U-shape groove 16 of semi-circular cross section.

Mounted for vertical reciprocation above the die 14 there is an upper die 18, carried by a die pad 20 and having a U-shape groove 22 complementary to the aforesaid groove 16.

The upper die pad 20 is secured to a plate 24 mounted, as by the adjustable nuts 26, upon vertical posts 28 connected, in turn, to a lower plate 30 carried by the piston rod 32 of a hydraulic piston and cylinder assembly 34 which is operable to move the upper die 18 upwardly and downwardly with respect to the lower die 14.

The upper and lower dies are mounted upon their respective die pads so that their U-shape grooves lie exactly opposite one another, whereby when the upper die 18 is closed upon the lower die 14 the grooves 16 and 22 combine to form an enclosed tubular U of circular cross section.

2

Vertical posts 36, secured to the upper die, engage in aligned bores in the upper die and serve to form guide posts. Slots 38 in the surfaces of the dies presented to their respective die pads form key guides by which the dies are accurately alignable to position their U-shape grooves in exact opposition.

In their fully closed position the mated die grooves are completely closed except at the outer ends of the legs of the U, where, as seen clearly in Figs. 1 and 4, a pressure ram 40 is positioned in one leg 42 and a back-up pressure ram 44 is positioned in the other leg 46.

Pressure ram 40 is connected with a hydraulic piston and cylinder assembly 48 so as to be reciprocable with respect to the leg 42, while back-up pressure ram 44 is connected for likewise operation by a hydraulic piston and cylinder assembly 50. Tie bars 52 (Fig. 1) connect the assembly 50 to actuate the back-up ram 44, this ram being secured to a plate 34 to which the said tie rods are secured and which plate operates in a guide 56.

Mounted within the U-shape groove 16 of the lower die are a series of hard ball elements 58 which, in operation, form, in effect a flexible extension of the back-up ram and lie in tandem arrangement between a pressure pad 60 at the inner end of the ram 44 and the inner end 25 of the tubular workpiece 62 to be operated upon. These ball elements are capable of moving along the curved bend 64 of the U-shape die groove, in advance of the workpiece, as will be understood.

To prepare the workpiece 62 for operation upon for bending to the shape of the U-shape die groove the workpiece is filled with a suitable filler, indicated at 66 in Fig. 5, which filler will hold the tubular workpiece against collapse and will preclude any appreciable thinning of the workpiece wall. A suitable filler is a lead alloy 35 material known under the registered trademark "Cerro-base." The material should be capable of being filled into the tubular workpiece and of being readily removable, as by melting, in which case the heat necessary will be such as will not adversely affect the workpiece. The filler material specified fulfills the requirements. It is malleable, inert to such material as aluminum, steel, and copper and has a relatively low melting point.

The pressure ram is shown fitted with a cylindrical pad of an external diameter and thickness equivalent to 45 that of the workpiece, whereas the ram itself is of a diameter, as seen particularly in Fig. 5, that it presents an inner end portion 70 which is capable of contacting one end of the filler 66 in entering relation to the tube 62, with the pad having reciprocable guiding relation to 50 the groove leg 42.

In operation, with the upper die 18 held raised, a tubular workpiece filled with a filler, as seen in Fig. 5, is inserted in the leg 42 of the lower die, the pressure ram 40 being in retracted position and the back-up ram 44 being in projected position, all as seen in Fig. 4. With the inner end of the workpiece constituting a leading end and the opposite end constituting a trailing end.

With the parts positioned as seen in Fig. 4, lubricant 60 is applied to the exterior surface of the workpiece and the upper die 18 is closed upon the lower die by actuation of the piston and cylinder assembly 34. Pressure is then applied to the pressure ram 40 to force the pad 68 against the adjacent end of the workpiece 62, as described with reference to Fig. 5, at the same time as the ram end portion 70 exerts pressure against the corresponding end of the filler 66. At the same time, back-up ram 44 exerts an opposing pressure, through operation of the piston and cylinder assembly 50, against the ball assembly 58 and this, by the partial entry of the ball 58' 65 into the corresponding end of the workpiece will exert pressure against the filler 66 and the adjacent tube end 70.

in opposition to the pressure exerted by the pressure ram portion 70 and the pad 68.

The pressure exerted by back-up ram 44 is capable of being over-ridden, as by the provision of a suitable relief valve (not shown) in the hydraulic system, by the pressure exerted by the pressure ram 40. This ram, therefore, will operate to push the workpiece 62 forward and around the bend of the closed die groove, with attendant bending of the workpiece to conform with the shape of the bend 64 and receding of the back-up ram. Upon completion of the bending operation the upper die is raised and the bent workpiece removed from the lower die. The bent tube is then cleaned to remove adherent lubricant and the filler removed, leaving the finished tube bend 72 as shown in Fig. 6. With the present machine, it is only necessary to employ standard lubricants, which can be easily removed and leave a lubricant clean surface which will permit adequate braze penetration when, as is usual, the tube bends or elbows are brazed to adjoining pipe or conduit ends.

I claim:

In a machine for forming tube bends up to 180° from tube sections pre-filled with a malleable filler medium for holding the tube sections against collapse during bending, support structure, die structure defining a tubular curved bend of 180°, means mounting said die structure for movement upon said support structure to open and close said tubular curved die bend, said bend including parallel straight end portions, a pressure applying ram, a back-up pressure ram parallel to said pressure applying ram, means mounting said pressure ram for reciprocation in one of said straight end portions, means mounting said back-up pressure ram for reciprocation in the other

straight end portion, a plurality of contiguous ball elements of slightly less diameter than the bore of said tubular curved die bend movable around and located within said die bend, said balls being sufficient in number to extend the length of said die bend whereby balls will simultaneously be in alignment with both of said straight end portions, one of said balls engaging said back-up ram whereby said plurality of balls form a flexible extension of said back-up ram, said tubular die bend adapted to axially receive a filled tube section under opposed endwise pressure by said pressure ram and said back-up ram while situated endwise between the inner end of the pressure ram and the back-up ram extension means, said ball elements exerting pressure against one end of the filled tube section and said filler medium in opposition to a greater pressure exerted against the opposite end of said tube section and said filler medium by said pressure ram whereby said ball elements will move around said die bend as the pressure ram overcomes the pressure exerted by said back-up ram.
